PHONOGRAPH.

Application filed October 29, 1926. Serial No. 145,021.

This invention relates to phonographs, the primary object of the invention being to provide a record and means for controlling the playing thereof which will enable the 5 playing of much longer records than is possible with devices heretofore used.

In carrying out my invention it is, of course, necessary to make a record in a manner very similar to that in which the record 10 is played but we shall hereinafter set forth our invention in connection with means for playing a record.

Undoubtedly the most serious defect of the disk type of talking machine record is 15 the fact that nothing requiring more than about four minutes to play can be recorded entire on the ordinary disk record. It would be possible to increase the time capacity by using records of larger diameter, but the in- 20 crease in time capacity would be so small compared to the increase in bulk of the record that it loses any practical advantage.

If instead of operating the turntable at a 25 constant speed (78 R. P. M. in current practice), the turntable were operated at an accelerated speed, so that the travel of the groove under the needle would be at a constant speed measured in inches per minute, much more time value could be gotten out 30 of the present diameter of record, and increases in diameter, if adopted, would justify themselves by affording much greater increases in time value.

For example, the playing part of a twelve- 35 inch record will extend from an outside diameter of about eleven and a half inches to an inside diameter of about four and a half inches. The spaces outside and inside those points are margin and center, respectively. 40 With a constant speed under the needle, the circumference at the outside limit, thirty six and a tenth inches, would have more than two and one half times as much time value as the circumference of 14.2 inches at the inside limit. If the present rate of speed 45 under the needle at the inside limit (about 1100 inches per minute) were adopted as standard, the present twelve-inch record, with the present width of groove, could play 50 more than seven minutes, as contrasted with the four-minute limit when played as at present with constant revolutions per minute. An added inch of diameter would increase the time capacity to 9.7 minutes. A 55 fifteen-inch record would have a time capac-

ity of about 14 minutes, which would permit the recording without mutilation of even most symphony movements.

An added advantage would be in the uniform conditions of recording and reproduction that a constant speed of travel would give. With the constant R. P. M. as now used, a speed exactly right at the periphery would be so slow at the center that the tone when playing near the center would be deadened. A speed just right at the center would be so fast at the periphery as to cause excessive scratchiness. It is necessary to compromise, arranging conditions so that the optimum speed is about midway between these 60 two extremes. No compromise need be adopted with the constant speed of travel. All the record would be played at the optimum speed. When thus freed from the necessity of producing records to play successfully at a wide range of speed, it might be found possible, by reducing the speed and getting more grooves to the inch of diameter, to produce a twelve-inch record that would 65 play fifteen or twenty minutes.

Two serious practical difficulties stand in the way of a change from the constant R. P. M. to a constant rate of travel:

1. Any variation between the rate of acceleration of the turntable used in recording 70 and the rate of acceleration in the reproducing instrument causes the record to play out of tune. No device which is appreciably affected by the weather, temperature, strength of springs, etc., will be satisfactory. 75 No device merely approximating to a constant speed of travel through acceleration of the turntable will be satisfactory, because all the individual machines of that make offered on the market would have to be 80 synchronized with each other to a degree of accuracy not mechanically possible, in order that all of them could play equally 85 true to pitch any records made to be used on them. An acceleration giving exactly 85 constant rate of travel permits more freedom. Just as a record is equally well in tune under the present method whether played at 65 or 78 R. P. M., so a record 90 would be equally well in tune whether played at 1100 or 1200 inches per minute. All that is necessary is that the rate be 95 constant throughout the playing of the record.

2. Any device of this sort should permit 100

of being disconnected, so that the turntable could be made to rotate at constant R. P. M. when desired. This is a commercial necessity, because both manufacturers and consumers would hesitate long to adopt a machine that made all the present records unavailable. If the accelerating device can be disconnected at will, it preserves the availability of all present resources while adding a new one.

10 The device to be described meets both of these requirements by a simple mechanism, which can be constructed to apply to the machines now in the homes, without any 15 alteration of the motor mechanism.

In the standard type of machine, the speed of the turntable is controlled by a 20 governor, and can be varied by turning the knurled knob of a speed regulator. Experiment shows that, within the effective limits 25 of the governor's functioning, the increase or decrease in R. P. M. for each degree of turning of the speed regulator is at a constant rate. Experiment also indicates that 30 the governor responds to the action of the regulator with a high degree of accuracy. Therefore, by simply linking the speed regulator to the tone arm, so that the travel of the tone arm in playing will turn the regulator, 35 we have a simple and accurate method of varying the R. P. M. of the turntable to correspond to the position of the needle on the record. This is the essential principle of the device to be described.

35 With these and other objects in view, the invention consists in certain novel features of construction and combinations and arrangements of parts, to be more fully described hereinafter and pointed out in the 40 claims.

In the accompanying drawings is illustrated one embodiment of our invention—

45 Figure 1 is a view, partly in elevation and partly in section, illustrating my improved attachment in connection with a standard type of phonograph;

Figure 2 is an enlarged view in section on the line 2—2 of Figure 1;

50 Figure 3 is a fragmentary view in vertical section through the mounting of the upper portion of the controller shaft;

Figure 4 is a fragmentary view, partly in elevation and partly in section, showing the mounting of the arm on the controller shaft;

55 Figure 5 is a fragmentary plan view of the record and the tone arm and sound box.

1 represents a box or cabinet in which a 60 frame 2 is secured and supports a spring motor 3 which through the medium of a pinion 4 and a gear wheel 5 transmits motion to a shaft 6 on which a turntable 7 is mounted. This turntable 7 supports the record disk 8, the groove of which is engaged by a needle 9 on the sound box 10 carried by tone arm 11. The parts above described

are standard equipment and need not be described in detail.

On the shaft 6 a large gear wheel 12 is fixed which engages a pinion 13 on a governor shaft 14, the latter carrying outwardly 70 movable arms constituting a governor 15 and a disk 16 to which the arms 15 are connected. 17 represents a controller shaft which projects through an opening 18 in cabinet 1 and at its lower end is mounted 75 in a bracket 19. This shaft 17 adjacent its upper end carries a pinion 20, and an adjusting button 21 is mounted on the upper end of the shaft and has an opening 22 therein receiving a grooved portion 23 of 80 shaft 17, so that the button and shaft are coupled to move vertically together but permit free turning movement of the shaft.

This button 21 has an enlarged externally 85 screw-threaded lower end 24 which meshes with an internally screw-threaded opening 25 in an angle bracket 26. This angle bracket 26 is secured to the box or cabinet 1, and an arcuate angle plate 27 is also secured to the cabinet 1 and is offset upwardly at 90 its center edge to accommodate thereunder the toothed end of a segment 28. The segment 28 is secured to the tone arm 11 and meshes with pinion 20.

On the controller shaft 17 I locate sleeve 95 29 which covers a screw threaded portion 30 of shaft 17 and has one or more pins 31 projecting into the threaded portion of the shaft so that when the shaft turns the sleeve is moved longitudinally on the shaft, as 100 will be readily understood.

The sleeve 29 carries a tubular extension 32, projecting at right angles thereto and supporting an arm 33 which telescopes in the extension 32 and is adjustably secured 105 therein by means of a set screw 34. The arm 33 projects through a slot 35 in frame 2 to prevent lateral movement of the arm, and at the free end of said arm a shoe 36 is provided to engage the underface of disk 110 16. This attachment above described may be readily secured to any ordinary type of phonograph in general use with but slight expense.

In operation the speed of the disk 8 is 115 varied during the playing of the record and this variation in speed is entirely automatic. By reason of the mechanism above described the turning of the record is slowest while the needle is in the outer groove, and the 120 speed of movement of the record increases in relative proportion as the needle moves radially and inwardly of the disk, so that the highest speed of the record is when the needle is in the innermost groove.

125 In referring to the speed as highest and lowest we would have it understood that the high speed of our record is substantially the same as the normal speed of the record now in use, so that the speed of the record 130

when the needle is in the outer groove is very appreciably less than the speed of the records in common use.

While we have illustrated a particular apparatus for carrying out this idea we would have it understood that we do not wish to be limited to particular details of construction but desire to cover broadly the idea of means which vary the speed of the record as the needle moves radially of the record so that, for example, a bar of music requires only the same length of groove at the outer portion of the record as it does at the inner portion of the record.

15 This invention, as above stated, includes the idea broadly of the provision of a record adapted for playing in connection with apparatus, as above defined.

Various slight changes and alterations 20 might be made in the general form of the parts described without departing from the invention and hence we do not limit ourselves to the precise details set forth but consider ourselves at liberty to make such changes and alterations as fairly fall within the spirit and scope of the appended claims.

We claim:

1. The combination with a phonograph 30 having a turntable and a movable tone arm, of a governor operatively connected to the driving mechanism of the turntable, a controller shaft caused to turn by the movement of the tone arm, and means operated by the turning movement of the controller shaft to 35 control the operation of the governor, said last-mentioned means including an arm having screw-threaded engagement with the shaft, and a disk on the governor engaged by the arm.

40 2. The combination with a phonograph

having a turntable and a tone arm, of a governor operatively connected to the driving mechanism of the turntable, a controller shaft, a pinion on the controller shaft, a segment on the tone arm meshing with the 45 pinion, a sleeve having screw-threaded engagement with the controller shaft, an arm adjustably connected to the sleeve, a shoe on the arm, and a disk on the governor engaged by the shoe.

3. The combination with a phonograph 50 having a turntable and a tone arm, of a governor operatively connected to the driving mechanism of the turntable, a controller shaft, a pinion on the controller shaft, a 55 segment on the tone arm meshing with the pinion, a sleeve having screw-threaded engagement with the controller shaft, an arm adjustably connected to the sleeve, a shoe on the arm, a disk on the governor engaged 60 by the shoe, and means for adjusting the controller shaft longitudinally.

4. The combination with a phonograph 65 having a turntable and a tone arm, of a governor operatively connected to the driving mechanism of the turntable, a controller shaft, a pinion on the controller shaft, a segment on the tone arm meshing with the 70 pinion, a sleeve having screw-threaded engagement with the controller shaft, an arm adjustably connected to the sleeve, a shoe on the arm, a disk on the governor engaged by the shoe, a bracket, and a button having screw threaded engagement with the bracket 75 and operatively connected to the shaft whereby the manual turning of the button adjusts the controller shaft longitudinally.
